US0D1054656S

(12) **United States Design Patent** (10) **Patent No.:** **US D1,054,656 S**
(45) **Date of Patent:** **** Dec. 24, 2024**

(54) **SHOE**

(71) Applicant: **PUMA SE**, Herzogenaurach (DE)

(72) Inventors: **Romain Girard**, Lauf an der Pegnitz (DE); **Matthias Hartmann**, Forchheim (DE)

(73) Assignee: **PUMA SE**, Herzogenaurach (DE)

(**) Term: **15 Years**

(21) Appl. No.: **29/845,375**

(22) Filed: **Jul. 7, 2022**

Related U.S. Application Data

(60) Continuation of application No. 29/734,668, filed on May 14, 2020, now Pat. No. Des. 960,541, which is a continuation of application No. 29/667,509, filed on Oct. 23, 2018, now Pat. No. Des. 887,113, which is a division of application No. 29/594,703, filed on Feb. 22, 2017, now Pat. No. Des. 850,766.

(30) **Foreign Application Priority Data**

CLAIM

The ornamental design for a shoe, as shown and described.

DESCRIPTION

FIG. 1 is a left side elevational view of an ornamental design for a shoe; and,

FIG. 2 is a rear elevational view of the shoe of FIG. 1. The dash-dash-dash lines are included for the purpose of illustrating portions of the shoe that form no part of the claimed design.

1 Claim, 2 Drawing Sheets
